[57] CLAIM

The ornamental design for a combined pen/pencil and memo pad holder, as shown and described.

DESCRIPTION

FIG. 1 is a top, front and right side perspective view of a combined pen/pencil and memo pad holder showing my new design;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a bottom plan view thereof, partially broken away for clarity of illustration;

FIG. 7 is a sectional view thereof, taken along line 7—7 of FIG. 5; and

FIG. 8 is a sectional view thereof, taken along line 8—8 of FIG. 7.
